RANSLOE BOONE ABBOTT, OF READING, PENNSYLVANIA.

INSULATED RAIL JOINT.

Application filed June 16, 1926. Serial No. 116,292.

This invention described herein relates to improvements in insulated joints for rail-ways and has for its object to produce a simplified and improved structure having 5 important advantages over structures as heretofore proposed and used.

My improved insulated joint is of the type employing insulating wood filler blocks engaging the fishing surfaces of the respective 10 rail ends which are held in position by the usual securing bolts with interposed angle bars having their base flanges underlying the rail ends for the purpose of giving adequate vertical support thereto. An important 15 objection to insulating joint structures of this type as heretofore proposed has resulted from the arrangement providing for the securing of the angle bar supports to the ties at opposite sides, from which it results 20 that under the action of the longitudinal creeping and wave movement of the rail the securing devices in their action cause a relative movement of the parts of which the joint is composed, particularly accentuated 25 under conditions of loosened or partially loosened bolts, and the effect of which is to produce excessive wear upon the insulation employed. In my improved 30 structure this excessive wear of the insulation is to a large degree eliminated by an improved structural form which allows of securing the angle bar supports at one side only as is required for the purpose of maintaining gauge thereby providing for substantially 35 free vertical movement of the joint structure as a whole under the rail wave action with reduced relative movement of the parts and lessened wear upon the insulation. Incidental to the important 40 advantages referred to, my improved arrangement allows of employing angle bar supports composed of standard rolled sections offering substantial facility and economy of manufacture.

The described and other features and advantages of my improved insulated joint structure will be more fully understood by reference to the accompanying drawings 45 wherein like reference characters are applied to the corresponding parts in the several views.

In the drawings,

Fig. 1 is a view in side elevation illustrating an improved embodiment of the features 55 of my present invention.

Fig. 2 is a vertical cross sectional view thereof.

In the preferred structural embodiment of my invention as here illustrated, 1 and 2 indicate the respective rail ends to be joined. 60 The joint structure comprises the oppositely positioned and reversely arranged angle bars 3 and 4 having their base flanges 5 and 6 extending beneath the rail ends in overlapping relation whereby the flange 6 of 65 upper angle bar 4 bears upon the base flange 5 of the angle bar 3 to afford base support to the rail ends, the angle bars being of corresponding length and adapted to span adjacent ties to supply bridge support in the 70 usual manner. Between the vertical members of the angle bars 3 and 4 and the rail ends, there are positioned insulating wood filler blocks 7 and 8 of a length corresponding to the length of the angle bars and 75 formed to have fishing engagement with the underside of the rail head and the upper surface of the rail flanges and having vertical outer surfaces as shown. An angular fibre insulating member 10 is, as shown, disposed with its vertical portion between the outer surface of filler block 8 and the vertical portion of angle bar 4 and with its horizontal portion 11 positioned between the rail ends and the upper surface of the horizontal flange 6 of angle bar 4 thereby to provide base insulation for each of the rail ends. 80 For the latter purpose, the insulating member 10-11 may desirably extend, as shown, the full length of the joint structure. 85 For securing the respective parts in operating position the usual securing bolts 12 are fitted to apertures in the angle bar and fillet block members and in the rail ends. The bolts have the usual squared heads 13 90 with their opposite ends threaded to receive the securing nuts 14 and they are insulated from the angle bar members by means of the usual fibre washers 16-16 and fibre insulated bushings 17 fitting in large openings 100 in the angle bars and are protected by the usual outwardly positioned metal washers 18-18.

An important feature of my improved construction results from the employment of 105 the plane or standard type angle bars which in addition to offering greater facility and economy of manufacture have desirable features of advantage in the assembled joint. In practice I have found that in an insulated 110

joint of this type it is very desirable that the joint structure shall be to a large degree non-secured against vertical movement, whereby the joint structure as a whole may be movable to conform to the normal wave motion of the rail. The employment of the standard or plain angle bars having a plane outer vertical surface structurally provides that at one side, as here shown at the left, the angle bar support cannot be secured by the usual track fastener or spike. With respect to the opposite side of the joint structure, while the ideal arrangement would be to have a lower angle bar flange non-projecting and in consequence non-susceptible of spiking, for practical purposes, it is essential that the outer side spikes be employed for the purpose of maintaining the track to gauge. It is accordingly provided that the lowermost angle bar flange shall project outwardly beyond the outer face of the vertical member 4 of the upper angle bar, thereby providing for spiking at one side only. This spiking at one side for maintaining gauge is found not to be substantially objectionable in restricting the vertical movement of the joint structure as a whole and causing relative movement of its parts as by reason of its parts having inadequate holding the spikes are lifted under the action of the wave movement sufficient to provide for a normal clearance therefor when ordinary spikes are employed. As here shown, screw spikes may preferably be employed and in their application may be screwed down to a position not quite in contact with the angle bar flange and to leave a normal vertical clearance sufficient to allow of the rail movement. It is important, however, that to attain the practical advantages of my improved structure at least one side of the construction shall have no provision for spiking, thereby to insure that its intended advantages shall be obtained, for as will be appreciated, if provision for spiking is present the tendency of the unskilled trackman would be to fully spike down the insulated joint as well as the common joint under the practical conditions of track maintenance.

Having described my invention, I claim:

1. An insulated rail joint including the rails, oppositely positioned angle bar members for joining the rail ends, insulating members interposed between said angle bars and the rail ends, bolts for securing the angle bars in position, said bolts being insulated from said bars and the angle bar at least at one side of said joint structure being of a form and arrangement to prohibit spiking to the ties.

2. An insulated rail joint including the rails, oppositely positioned filler blocks positioned to engage the respective rail ends,

angle bars positioned with their vertical members opposed to the outer surfaces of the filler blocks and having their horizontal flanges oppositely extended in overlapped relation and underlying the rail ends to provide base support therefor, securing bolts fitted to apertures in the rail ends, filler blocks and angle bars, an insulating member of angular form interposed between the rail ends and the uppermost of said angle bars and having a vertical portion positioned between the filler blocks and said angle bar vertical member and said angle bars being composed of standard rolled steel sections whereby the joint structure, at least on one side, will have a plane vertical surface non-adapted for spiking to the ties.

3. An insulated rail joint including the rails, oppositely positioned filler blocks positioned to engage the respective rail ends, angle bars positioned with their vertical members opposed to the outer surfaces of the filler blocks and having their horizontal flanges oppositely extended in overlapped relation and underlying the rail ends to provide base support therefor, securing bolts fitted to apertures in the rail ends, filler blocks and angle bars, an insulating member of angular form interposed between the rail ends and the uppermost of said angle bars and having a vertical portion positioned between the filler blocks and said angle bar vertical member and said angle bars being composed of standard rolled steel sections providing at one side a plane vertical surface non-adapted for spiking to the ties and the lowermost of said angle bars having its horizontal flange at the opposite side extending beyond the vertical member of the upper angle bar to provide for spiking to maintain gauge.

4. An insulated rail joint including the rails, oppositely positioned filler blocks arranged to engage the respective rail ends, angle bars oppositely positioned with their vertical members opposed to the outer surfaces of the filler blocks and with their horizontal flanges underlying the rail ends to provide base support therefor, securing bolts fitted to apertures in the rail ends, filler blocks and angle bars, insulating means interposed between the bolts and said angle bars, insulation interposed between the rail ends and the uppermost angle bar and said angle bars being composed of standard rolled steel sections whereby the joint structure, at least on one side, will have a plane vertical surface non-adapted for spiking to the ties.

Signed at Reading, in the county of Berks and State of Pennsylvania, this 11th day of January, A. D. 1926.

RANSLOE BOONE ABBOTT.
